(57) **CLAIM**

We claim the ornamental design for a patient kit unit assembly to assist breast prosthesis decision making, as shown and described.

DESCRIPTION

FIG. 1 is an expanded top perspective view of the patient kit unit assembly to assist breast prosthesis decision making showing our kit design;

FIG. 2 is a bottom perspective view thereof;

FIG. 3 is a right side elevation view thereof, and left view, front view and rear view being identical;

FIG. 4 is a top plan view thereof;

FIG. 5 is a bottom plan view thereof; and,

FIG. 6 is an enlarged assembled top perspective view thereof. The broken lines shown in all Figures are for illustrative purposes only and form no part of the claimed design.
